UNITED STATES PATENT OFFICE.

CHARLES H. FULLER, OF PORTLAND, OREGON.

LIFEBOAT-DERRICK.

1,386,102.

Specification of Letters Patent.

Patented Aug. 2, 1921.

Application filed May 19, 1919. Serial No. 298,105.

To all whom it may concern:

Be it known that I, CHARLES H. FULLER, a citizen of the United States, residing in the city of Portland, county of Multnomah, and 5 State of Oregon, have invented a new and useful Lifeboat-Derrick, of which the following is a specification:

This invention relates more particularly to a means for operating a life boat between 10 the deck of a vessel and the water.

The object of my invention is to provide an exceedingly simple and efficient means for launching a life boat from the deck of a vessel as well as returning same to the deck 15 after having been launched.

I attain these objects in the manner described in the following specification and illustrated in the accompanying drawings, in which:

20 Figure 1 is a front elevation of my device showing the boat being lowered over the ship's side. Fig. 2 is an end elevation of Fig. 1. Fig. 3 is a side elevation of the boom head. Fig. 4 is a front elevation of same. Fig. 5 is a plan of the boom head. Fig. 6 is a sectional elevation along the line 11—11 in Fig. 5. Fig. 7 is a sectional elevation along the line 12—12 in Fig. 3. Fig. 8 is a diagrammatic view showing the relation of 25 the running parts of the line with the various sets of blocks, mast, boom and boat. Fig. 9 is a detailed plan of the boat block. Fig. 10 is a sectional view through line 15—15 in Fig. 9. Fig. 11 is a front elevation 30 of boat block. Fig. 12 is a front elevation of boom block which in one case is used as a boat block. Fig. 13 is a plan of Fig. 12. Fig. 14 is a sectional view along the line 19—19 in Fig. 13. Fig. 15 is a plan of 35 mast head. Fig. 16 is a side elevation of mast head. Fig. 17 is a sectional view through line 22—22 in Fig. 16. Fig. 18 is a side elevation of foot of boom. Fig. 19 is a front elevation of Fig. 18. Fig. 20 is a 40 plan of boom brace hinge. Fig. 21 is an elevation of same. Fig. 22 is a plan of the mast foot. Fig. 23 is an elevation of same. 45

Similar letters and numbers of reference refer to the same or similar parts throughout the several views.

Referring in detail to the drawings. Instead of the usual form of davit for the operation of a life boat I have constructed the mast A₁ which in this case rests upon the

top of the operating gear which is at one 55 end of the life boat. At the opposite end of the life boat is erected the mast A₂ which is supported on the foot A₃ in the socket A₄. On the foot A₃ is also erected the standard A₅ which carries the pin A₆ and acts as a 60 hinged joint for the foot of a boom. A₇ are mast heads which are mounted on A₁ and A₂ and are supplied with the eyes A₈ to which are secured the mast braces A₁₀ which are secured to the deck by eye bolts. A₁₁ is a 65 foot for the mast A₁ and is secured to the top of the operating winch. A₁₂ is a standard for the boom nearest the winch.

F₁ are booms which have boom joints F₂ at their lower ends which are adapted to receive the pins A₆ and form a hinged joint. F₃ are boom heads which are supplied with shanks F₄ which are adapted to slide into the hollow booms F₁. In the boom head F₃ are mounted the sheaves F₅ to F₁₂ inclusive, 70 the pin F₁₃ acting as a pivot for the sheaves F₅ and F₆. The bolts F₁₄ act as a pivot for the sheaves F₁₁ and F₁₂, and the bolts F₁₅ act as centers for the sheaves F₇, F₈, F₉ and F₁₀. F₁₆ is an eye on boom head F₃ for a stay between the boom heads. F₁₇ is a similar eye on the boom head for attaching a diagonal brace. F₁₈ is a stay between the boom heads, in which stay is placed the turn buckle F₁₉. F₂₀ is the diagonal brace which ties the eye 80 F₁₇ to the floor plate F₂₂ which is secured to the deck. The brace F₂₀ is made adjustable by the turn buckle F₂₁ and is joined to the floor plate F₂₂ by means of the bolts F₂₃.

In order to operate the lines safely, easily 90 and uniformly I have constructed a special form of winch which I will describe here only briefly. Against the hub H₄, which forms a part of the winch, is mounted a boat operating drum which is adapted to receive the inboard boat operating lines. The hand boat lever K₁₂ throws the boat operating drum in and out of gear. Against the other hub H₄, which forms a part of the winch, is mounted a boom operating drum 95 arranged to receive the outboard boom operating lines. The boom operating drum is controlled by the hand boom lever L₁₁.

Between the boat operating drum and the boom operating drum is mounted a worm 105 wheel driven by a worm carried by the shaft M₅. This worm wheel is adapted to be connected to either drum or to be free from both

of them at will. M_7 is an operating crank on the shaft M_5 through which rotation is supplied to either or both of the drums. M_8 are the outboard stops and M_9 the in-board stops on the boat lines.

Referring to the various blocks on my device O_1 is a direct mast block. O_2 is a near indirect mast block and O_3 is a far indirect mast block. O_4 is a double block to boat. O_5 is a single block to boat. O_6 is a far single block to boat. O_7 are the boat blocks and O_8 is a sheave in the block O_1 . O_9 are sheaves in the blocks O_2 , O_3 and O_6 . In the block O_4 is a large sheave O_{11} and a small sheave O_{12} . O_{13} is a sheave in the block O_5 . O_{15} is a sheave in the block O_7 . O_{16} are hooks secured to the boat blocks O_7 which engage the rings on the life boat.

Referring particularly to the various operations of the lines, R_1 represents the line which passes from the boat operating drum to the small sheave O_{12} . R_2 from O_{12} to the sheave O_{13} . R_3 from O_{13} to the sheave F_7 . R_4 from F_7 to the sheave F_6 . R_5 from F_6 to the sheave F_8 . R_6 from F_8 to the outboard stop M_8 on the boat line. R_7 from M_8 to the sheave O_{15} . R_8 from O_{15} to the inboard stop O_9 on the boat line. R_9 from M_9 to the sheave F_{12} . R_{10} from F_{12} to the sheave F_5 . R_{11} from F_5 to the sheave F_{10} . R_{12} from F_{10} to the mast head sheave A_8 . R_{13} from A_8 to the sheave O_8 . R_{14} from O_8 to the boom operating drum.

The operation of the lines at the farther end of the device, that is away from the winch, is as follows: The line S_1 extends from the boat operating drum to the sheave O_{11} . S_2 from O_{11} to the sheave O_9 in the block O_3 . S_3 represents the line which passes through the sheaves of the boom head and the boat block at the farther end of the boat, as above explained. S_4 from the boom head to the sheave A_8 on the mast head. S_5 from A_8 to the sheave O_9 in the block O_3 . S_6 from O_9 in block O_3 to the sheave O_9 in block O_2 . S_7 from O_9 in block O_2 to the drum L_1 .

T_1 is a life boat which contains a coil of boom control line which passes over the block T_2 on the stay F_{18} and thence over the sheave T_4 and down to the boom control line lever T_5 .

U_1 represents the boat control lever which actuates the boat line drum brake. U_{16} represents the ship's deck and U_{17} the boat control line which extends from the lever U_1 to the boat, in the same manner as does the boom control line T_2 . While the boat and boom lines may be controlled by the lines U_{17} and T_2 by the occupants of the boat T_1 , they may also be controlled by action of a hand lever which controls the boom lines, and a second hand lever which controls the boat line. Each of the hand levers just mentioned will set their respec-

tive brakes when their free end is raised, and they may be held in position by engagement with ratchet teeth.

It will be very apparent to anyone familiar with this class of apparatus that it is very desirable in launching a life boat from the deck of a vessel to lower it into the water at a point which is as far from the ship's side as possible. This object I attain by means of the derrick-like construction of my device. Absolute control over the boom is maintained at all times, since the lines which operate the boom are opposed to each other and have a purchase on the boom from opposite sides of the boom center line at all times.

An inspection of Fig. 8, which is a diagrammatic view of one side of the lines, will very clearly show the principle involved in my invention. In this case A represents the center line of the inboard row of blocks. B is the center line of the boom controlling drum. C is the center line of the mast head. D is the center line of the boat controlling drum. E is the center line of the outboard row of blocks, and F is the center line of the boom head. While in this view I have not shown all of the intermediate sheaves required to change the direction and guide the lines involved, I have shown those which are sufficient to illustrate the principle which renders my device incapable of jacking, and also provides a remarkable control over the operation of the life boat.

It will be seen in Fig. 8 that with a limited supply of line on the boom operating drum that the stop M_9 will limit the outboard position of the boom. It will be understood that the stops M_8 and M_9 cannot pass through the sheaves in the boom head but are capable of being passed through the boat block O_7 . Therefore, if the life boat is to be lowered beyond a point which is outside of the reach of the boom, any further descent of the boat could only be accomplished by playing out the lines from the boat operating drum, in which event the stop M_8 will pass through the boat block O_7 and the boat will descend as permitted by the boat line drum brake.

Special attention is called to the fact that on account of the peculiar construction of my device the booms may be operated in-board as well as outboard with an equal degree of control, which feature permits the bringing up of boats from storage or from between decks, provided the apparatus is placed within range of a suitable hatchway, which will effect a considerable saving in deck space, as well as the number of derricks for handling the boats.

Of course in the launching of boats from their position between the masts it is easily seen that the boat must first be lifted clear of its chucks, and if not resting on chucks

then it must be clear of the deck during its outward travel. However, as soon as the boat has passed overboard then both the boat and the boom lines may be played out 5 at the same time, which operation is accomplished by releasing the respective brakes, the work being done by gravity.

While I have thus illustrated and described my invention it is not my desire to 10 limit myself to this precise form or method of application of my invention, but intend that it shall cover all forms and modifications that fall fairly within the appended claims.

15 What I claim as new and desire to protect by Letters Patent of the United States is:

1. A life boat derrick consisting of a pair of derricks adapted to receive a life boat between them, each derrick consisting of a 20 vertical mast mounted on a deck and having a boom hinged near its foot, a hauling line arranged to pass from a point on the deck inboard from said mast, over the top of said mast, thence over the head of said boom to 25 a boat block, thence back through said boom head to a point on the deck outboard from said mast.

2. A life boat derrick consisting of a pair of derricks adapted to receive a life boat 30 between them, each derrick consisting of a vertical mast mounted on a deck and having a boom hinged near its foot, a hauling line arranged to pass from a point on the deck inboard from said mast, over the top 35 of said mast, thence over the head of said

boom to a boat block, thence through said boom head to a point on the deck outboard from said mast, and a winch member adapted to haul in and play out each end of said line member.

40

3. A life boat derrick consisting of a pair of derricks adapted to receive a life boat between them, each derrick consisting of a vertical mast mounted on a deck and having a boom hinged near its foot, a hauling line 45 arranged to pass from a point on the deck inboard from said mast, over the top of said mast, thence over the head of said boom to a boat block, thence through said boom head to a point on the deck outboard from 50 said mast, and a stop means consisting of two stop members secured to said line beyond said boom head and of a nature to permit same to pass through the boat block but not over said boom head.

55

4. A life boat derrick of the character described, in combination with a boom head consisting of a frame member mounted on the head of a swinging boom, four sheave members mounted in said frame in tandem 60 and in pairs in a plane parallel to the movement of said boom, direction changing sheaves mounted in said frame at right angles to, above and between the inner edge of each pair of first mentioned sheaves, and 65 a line guiding sheave mounted in the same plane below and between each tandem pair of first mentioned sheaves.

CHARLES H. FULLER.
